UNITED STATES PATENT OFFICE.

GEORGE H. WESSELING, OF ST. LOUIS, MISSOURI.

ROTARY CUTTER.

SPECIFICATION forming part of Letters Patent No. 394,803, dated December 18, 1888.

Application filed December 21, 1887. Serial No. 258,616. (No model.)

To all whom it may concern:

Be it known that I, GEORGE H. WESSELING, of the city of St. Louis, in the State of Missouri, have invented a certain new and useful Improvement in Rotary Cutters, of which the following is a full, clear, and exact description, reference being had to the accompanying drawings, forming part of this specification, and in which—

Figure I is a back view of the machine with parts broken away to show the action of the slicer-disk with its geared periphery and the pinion that actuates the bevel-gear on the egg-beater shaft. It also shows the latch-hook that holds the nest of bean-hoppers in their place. Fig. II is an end view with parts broken away to show the action of the feeder, slicer, and internal gear. Fig. III is a vertical section taken on line III III, Fig. I, showing the slicer-disk, its set-screw attachment to its operating-shaft, and its geared connections with the rotary egg-beater shaft. Fig. IV is a detail view, part in section, of the feedway to the slicer and grater with the pivoted feed-shutter, the latter shown also in elevated operative position in dotted lines. Fig. V is a view in elevation of the egg-beater with part broken away to show the sleeve attachment to its rotary shaft. Fig. VI is a perspective view of the hoppers for attachment to the feedway when green beans or other small vegetables are to be sliced. Fig. VII is a vertical section of the grater-disk with the set-screw that secures it to its operating-shaft. Fig. VIII is an enlarged detail section of the grater-disk, showing one of the burrs in cross-section and Fig. IX is an enlarged detail perspective of said grater, showing the open mouth of the burr.

The invention relates to a domestic machine which, besides for household use, is also especially adapted for use in hotels, restaurants, bakeries, confectioneries, &c., for slicing vegetables, grating, and egg-beating purposes; and the invention consists in features of novelty hereinafter fully described, and pointed out in the claims.

Referring to the drawings, in which similar figures of reference indicate like parts in all the views, 1 represents the back, 2 the ends, and 3 the front and 4 the bottom bar, of the

frame, in and attached to which the various combined devices pertaining to this machine are secured.

5 is the clamp and 6 the set-screw, which are used to secure the frame to the table or bench 7 on which it stands. As shown, a long clamp is used, so that it will reach from the edge of the table to hold the bottom cross-bar whichever way the frame is set, either as in Fig. II or as in Fig. III. I have shown one clamp; but, especially in large machines, a second clamp may be used and found serviceable.

8 represents an inclined slide, preferably of tin, galvanized iron, or other sheet metal. The said slide is provided with a handle, 9, beneath it, for convenience in handling, and it runs in channel-grooves 10 in the end pieces that are formed on an incline from the back downward. This slide receives the slicings and gratings as they drop from the knives and grater and deposits them from its chute end 11 into any suitable vessels set to receive them.

12 is the main axle-shaft that carries the rotary slicer-disk 13 or rotary grater-disk 14. The said axle has its bearings, relatively, 15 and 16, in the front and back of the frame. The slicer has gates or openings 17 through 80 it for the passage of the sliced vegetables in the vicinity of the slicer-knives 18, which knives are secured to the disk by screws 19. The rake or thickness of the cut of the knives is regulated by set or thumb screws 20, that are seated in screw-threaded perforations in the disk, and as they are turned project against the knives and force them outward, and are thus made to regulate their rake and the consequent thickness of their cut.

90 The slicer-disk, which is preferably of cast or sheet iron, is secured to a hub, 21, at its center by any suitable means, and said hub has a projection back of the disk and a tubular bore, 22, within it for seating the main axle. A thumb-screw, 23, which has its screw-seat in the back projection of the hub, is made to screw down onto or into the axle to rigidify the connection of the disk to said axle and secure its rotation therewith when the machine is operated.

100 A pinion-wheel, 24, is keyed onto or near

the rear end of the main shaft, and its cogs 25 mesh into cogs 26 of the gear-wheel 27, which is keyed onto the operating-shaft 28, which has its bearings 29 and 30, relatively, 5 in the journal-box carrier-bar 31, which is secured in the rear of the frame and to the end pieces of the same by the screws 32, and in a journal-bracket, 33, which is secured to one of the end pieces of the frame by screws or 10 bolts 34. The journal-box carrier-bar 31, besides carrying the bearing 29 of the operating-axle, also carries the main axle-bearing 16 aforesaid. A cap-holder, 35, provided with a wooden or other suitable upper bearing- 15 cushion, 36, fits down over the main shaft at its near end to hold it in its bearings, and is secured at its rear end by the pivot-pin 37, on which it is raised to its open position shown in dotted lines, (see Fig. I,) when it is desired 20 to unship the shaft. A thumb-screw, 38, holds said cap home on the shaft when the machine is in operation.

39 represents the crank-handle that turns the machine. It is keyed or otherwise secured on the operating-shaft. I have shown the machine as turned by hand with a crank, as in all except very extensive establishments it would preferably be so worked; but it is evident that a drive-pulley could easily be 25 keyed on the end of the operating-shaft in the place of the crank-handle, and a pulley-band connect it with any suitable power.

The rotary grater-disk 14, made of tin, galvanized iron, or other suitable sheet metal, 35 has a hub, 40, secured to the center of the disk, and by radial arms 41 with the peripheral rim or tire 42, which hub is similar to that on the rotary slicer-disk, except that it is made slightly larger, so as to project farther 40 back from the disk and bring the grater-disk nearer to the front of the machine than the position in which the slicer works. The hub has an axle-bore, 43, in which, when the grater is used, the main axle is seated, and in which 45 it is rigidly secured by the thumb-screw 44, that screws onto or into it.

The grater-disk is provided with burrs or teeth 45, which may be stamped in the stub-pointed form shown in Fig. IX, or in the 50 pointed form shown on the disk view in Fig. VI. The burrs are projected in the direction that would best brace themselves in withstanding the force of contact with the material being grated. For this purpose they are 55 made to rake or point forward in the line of the rotary movement of the disk. It will be seen that this disposition of the inclined angle of the burr, besides bracing it to the best advantage, also makes of the burr a guide-slide 60 to direct and force the gratings through the aperture, from which they fall onto the inclined slide 8, which delivers them in the vessel placed at its discharge-chute to receive them. This form of burr is much better 65 adapted than is the common straight projecting-prong burr for withstanding the wear and tear of the work it has to perform, as it is in-

dividually a single strong burr, instead of, as is the common punched burr, a cluster of indefinite-shaped prongs that project out from 70 the body of the grater at about a right angle, and so at both a reverse angle to withstand the strain and have an inferior cutting and penetrating presentation to effect the grating; also, as it will be seen, these burrs, which are 75 machine-stamped of the same regular shape and inclination, angle back toward their base, so as, besides in their inclined presentation, they thus also brace themselves for the work 80 they have to perform.

46 represents the gate or opening in the front of the machine for the reception of the vegetables to be sliced or the material to be grated.

47 is the chute at said opening, and 48 side 85 pieces to the same.

49 is an extension-platform to the chute, which is pivotally secured thereto by metal hinge-brackets 50, that are secured to the extension-platform by screws 51 or otherwise, 90 and have projecting lugs or pivot-pins 52, that engage within the elongated slots 53 in the ends of the supply-chute and opening. An inclined pendent brace-bracket, 54, is secured by rivets or screws 55 to angle-brackets 56, that 95 are fastened to the under side of the extension-platform. A butt-flange, 57, on the lower end of the brace-bracket rests against the front piece of the frame beneath the chute when the bracket acts as a brace. When the 100 vegetables to be sliced or the material to be grated have been placed in the supply-chute, if the operator desires to use the extension-platform as a follower to advance the material in the supply-chute to the rotary slicer or 105 grater, as the case may be, and to firmly hold it while being operated on, he places his thumb within the circlet 58 and grasps the bracket with his fingers, then raises the combined platform and follower, turning it on 110 its pivotal connection 52 within the elongated slot 53, and, as it forces forward the material, sliding along said pivot-pin in the elongated slot until the slicing or grating is 115 completely effected, by which time the stop-projection 59 on the the outer end of the follower comes in contact with the front piece of the frame, which prevents the follower from coming in contact with the slicer or grater, as 120 the case may be.

60 represents the bean-hoppers, preferably made of cast or galvanized iron, which, as I show it, is formed of a row of three sectional hoppers, 61; but I do not confine myself to that number, for it may be varied to accord 125 with the size of the machine, &c. A bifurcated tongue, 62, is secured to the back cross-piece of the hopper, and when the hopper is placed in position at the supply-opening within the chute a pivoted latch-hook 63, that passes through the slot 64, between the prongs 65 of said bifurcated fork, and whose 130 pivotal end is seated in the front of the frame above the supply-chute, is turned down,

and thus holds the upper end of the hopper in position. A cross-strap, 66, secured to which are bows 67, is made, through its bows, to grasp the front of the sectional hopper and its flanged ends 68, which are passed through the perforations 69 in the side pieces of the chute and hold the hopper below to its seat.

70 represents cogs around the periphery of 10 the rotary disk of the slicer, which cogs engage with cogs 71 around the pinion-wheel 72, which is rigidly secured on a short thumb-screw shaft, 73, the screw-threaded end of which engages within the screw-threaded annular shaft 74, that has its inner bearing, 75, near the top of the front casing of this frame. A knob, 76, at the opposite end of the screw-shaft 73 serves to turn it into engagement with the annular shaft when the egg-beater annex 15 is set up. A flange-collar, 77, around the annular shaft holds the shaft to its right position longitudinally and backs up the bevel pinion-wheel 78, that is rigidly secured to it, so that it cannot slip its engagement with the 20 bevel pinion-wheel 79, which is rigidly secured on the upper end of the vertical rotary shaft 80, that carries and works the egg-beater 25 81. A bracket journal-box carrier, 82, secured to the front casing of the frame, incases and 30 carries the double journal-box 83, which has a horizontal bearing, 84, for the outer solid spindle end of the annular shaft 74, where it projects beyond the bevel-pinion 78, that it carries, and also provides the vertical socket 35 85 for the upper end of the rotary shaft that carries the egg-beater. A second bracket, 86, secured lower down, also to the front of the frame-easing, provides the bearing 87 for the egg-beater shaft.

40 The bracket 82, besides carrying the aforesaid double journal-box, also incases and carries a short conical-headed stud, 88, on which is pivoted a short strap, 89, that is furnished with a cap, 90, at its free end, which when 45 turned round, so as to surmount the rotary egg-beater rod with its bevel-pinion 79, keeps it from working up out of engagement with the bevel-pinion 78. When it is desired to remove said rod after the detachment of the 50 egg-beater, the strap 89 can be turned round, and the rotary shaft is then easily lifted out of its seat.

The egg-beater 81 may be of the common pear-shaped form of rotary egg-beaters, with 55 steel bow-beaters 91 secured to a central stem, 92, at both ends of the bow, with a round foot-button, 93, at the bottom of the stem, so that if it should rest on the bottom of the bowl or other vessel that contains the eggs and in 60 which it works the button will prevent the bows from friction against the bottom of the bowl; but the beater will work without the button touching the bowl, for the rotary shaft has bearings sufficiently apart from each other 65 to insure the steady movement of the beater.

I do not confine myself to this especial form of beater. It may be of any suitable construc-

tion that will effect its work in combination with my machine.

There is a socket, 94, formed in the enlarged 70 upper end of the central stem of the beater, of a size and form to fit as a sleeve around the lower end of the rotary shaft 80, and a collar, 95, surrounds the upper end of said socket. A milled-disk thumb-screw, 96, turning in its screw-seat 97, contacts with the rotary shaft and rigidly fastens the egg-beater thereto.

98 represents a (preferably sheet metal) partition casing of tin, galvanized iron, or other 80 suitable material. The upper end of said casing is turned at a right angle, and when in position forms a horizontal cover, 99, that surrounds the slicing and grating devices. The vertical part of said partition-easing (when being placed in position) is run down the vertical channel-grooves 100 in the inner sides of the end pieces until its lower end reaches the inclined slide 8. An elongated slot, 101, is formed in the lower portion of the casing to 90 enable it to pass the main axle, which it does back of the shoulder 102 thereon. The said shoulder provides a rigid backing for the hubs that relatively carry the slicer and grater disks.

95 The partition-easing consummates the isolation of the slicing and grating chamber of the machine, so as to keep dust and dirt from entering the chamber and contaminating the material being operated on. It also prevents 100 particles of the slicings and gratings from flying back among the gearing.

It will be seen, as shown and described, that the several parts of this machine are readily set up and taken apart, according to the varied work that it has to perform; and not only is it conformable to its change of work, but also the slicer-knives are easily adjusted to the thickness of the slices they are required to cut by varying the rake of their projected 110 edges by the action of the thumb or set screws; also, the pivoted extension-platform when it is elevated and slid forward, so as to become a follower, forces the material home to the action of the rotary slicer or grate, as the case 115 may be, and besides being more effectual than the operator's hands in effecting that purpose it also avoids all danger of injury to his hands from their coming in contact with the knives of the slicer of the grater.

120 The egg-beater, being detachable at its sleeve-connection with the rotary shaft, as stated, (to which it is secured by a set-screw,) is a valuable feature, as it requires cleaning each time it is used.

I claim as my invention—

1. The combination of the frame, the main shaft having bearings in the frame, the hub secured to the main shaft, the disk secured to the hub, the chute having side pieces formed 130 with grooves, the extension-platform brackets secured to the extension-platform having pivots occupying the grooves, and the pendent brace-bracket, substantially as described.

2. The combination of the frame, the main shaft having bearings in the frame, the hub secured to the main shaft, the disk secured to the hub, the chute having side pieces formed with grooves, the extension-platform brackets having pivots securing the platform to the side pieces, and the pendent brace-bracket having a circlet, substantially as described.
3. The combination of the frame, the main shaft having bearings in the frame, the hub secured to the main shaft, the disk secured to the hub, having cogs around the periphery, the bracket, the double journal-box having a vertical socket and horizontal bearing, the counter-shaft having a pinion meshing with the cogs and a bevel gear-wheel, and the shaft having bevel gear-wheel meshing with the bevel gear-wheel on the counter-shaft, substantially as described.
4. The combination of the frame, the rotary disk having cogs, the main axle-shaft on which the disk is mounted, the operating-shaft, the gear-wheels which connect the operating-

shaft with the main axle-shaft, the crank-handle by which the operating-shaft is turned, 25 the bracket, the vertical shaft, the double journal-box, and the drive-gear which connects the disk with the vertical shaft, substantially as described.

5. The combination of the frame having a 30 feed-supply opening, the rotary disk, the hand-crank, the drive-gear which operates the disk, the chute having elongated slots, the extension-platform pivoted in the elongated slots, the brace-bracket which supports the platform, 35 and the stop on the end of the platform, substantially as described.

6. The combination of the frame having a feed-opening, the chute having slots, the extension pivoted in the slots, and the brace- 40 bracket having circlet, substantially as described.

GEORGE H. WESSELING.

In presence of—
